UNITED STATES PATENT OFFICE.

SOLOMON L. GROSS, OF DES MOINES, IOWA.

SAD-IRON.

SPECIFICATION forming part of Letters Patent No. 662,932, dated December 4, 1900.

Application filed February 2, 1898. Renewed April 7, 1900. Serial No. 11,996. (No model.)

To all whom it may concern:

Be it known that I, SOLOMON L. GROSS, a citizen of the United States of America, and a resident of Des Moines, in the county of Polk and State of Iowa, have invented a new and useful Sad-Iron, of which the following is a specification.

One object of this invention is to provide improved means for heating and maintaining at a heated temperature a sad-iron.

A further object of this invention is to be found in the provision of means for insuring the full and complete vaporization of the liquid employed as the heating medium.

15 A further object of this invention is to be found in the provision of means for removing and separating out from the heating medium all sediment or foreign substances in advance of the vaporization thereof.

20 A further object of this invention is to be found in the provision of a tank or reservoir made of a single piece of metal by casting.

The objects of this invention, as above stated, are attained by the construction, arrangement, and combination of elements hereinafter set forth, pointed out in my claims, and illustrated by the accompanying drawings, in which—

Figure 1 is a perspective of the complete device in the form for practical use. Fig. 2 is a sectional elevation longitudinally of the device. Fig. 3 is an enlarged sectional view showing screen in trap. Fig. 4 is a plan of the device, the lid being removed and the supply-pipe broken off.

35 In the construction of the device, as shown, the numeral 10 designates a sad-iron formed with the concavity 11 in the upper portion thereof, which concavity is covered by a lid 12, carrying standards 13 14, to which a handle 15 is attached, a shield 16 being interposed between the handle 15 and the cover 12. The forward end portion of the cover 12 rests beneath a shoulder or shoulders 12^a on the upper portion of the end of the sad-iron 10, and the heel of the cover engages with a flange 17 on the heel of the sad-iron and is secured thereto by a set-screw 18, screw-seated in said flange and engaging the rear end of the cover.

50 A generator is provided and secured to the

rear portion of the sad-iron 10 by flanges 17^a 17^b, extended horizontally laterally from the generator and fixed by screws or bolts 19 19^a to the rear end of the sad-iron. The generator comprises a chamber 20 in its upper forward portion, into which is screw-seated a supply-pipe 21. The supply-pipe 21 extends forwardly through the concavity 11 of the sad-iron and is curved upwardly at its forward end in front of the handle of the device. A reservoir, tank, or receptacle 22 is provided, which is made of a single piece of metal, preferably brass, by casting, and is provided with a screw-threaded hub on its lower end, so shaped as to receive the screw-threaded upper and forward end portion of the supply-pipe 21. A boss 23 is formed integrally on the upper end of the tank 22 and has a closing-cap 24, mounted by screw-seating thereon, a gasket 25 being interposed between the bossed portion and closing-cap sealing the entrance to the tank. The chamber 20 is of greater length than the portion of the supply-pipe contained therein and is of greater diameter than the interior diameter of said supply-pipe, thereby forming a trap into which the sediment and foreign substances of the heating medium naturally precipitate and remain. The generator further comprises a communicating port 26, leading from the upper rear portion of the chamber 20 horizontally rearwardly to and communicating with the top of the well 27, vertically positioned in the rear portion of the generator. The well is drilled in the generator from the top thereof and closed at its upper end by a plug 28, screw-seated therein. The lower end portion of the well 27 communicates through a passage 29 with a discharge-port formed in and horizontally of the rear portion of the generator, which discharge-port contains and is controlled by a needle-valve 30, horizontally screw-seated in the generator in a plane intersecting the vertical plane of the well 27, which needle-valve is provided with an angular outer end portion, so shaped as to be engaged by a key or wrench to rotate said valve. A burner 31 is centrally located in the concavity 11 of the sad-iron and is formed of a tube or cylinder closed at its forward end and open at its rear 100

end, the rear end portion of the tube being screw-seated in the forward portion of the generator in alinement with the needle-valve 30 and in such position as that the discharge-5 port is axially of the tube. A series of perforations 32 are formed in the lower portion of the burner 31 and directed downwardly therefrom. A vaporizing-ball 33 is located in the lower portion of the well 27, the diameter of which ball is only slightly less than the diameter of the well. On the sides of the sad-iron, at the points of contact of the cover therewith, there are formed notches 11^a to permit of the escape from the concavity 11 of 10 the vapors and gases produced therein by the operation hereinafter described.

In practical use I fill the tank 22 with gasoline, alcohol, or similar fluid, open the discharge-port by the rotation of the needle-20 valve 30, and open the closing-cap of the tank slightly. The fluid then flows from the tank through the supply-pipe 21 into the chamber 20, through the communicating passage or port 26 into the well 27, around the vaporizing-ball in the well, through the passage 29 and discharge-port into a drip-cup 34 in the heel of the sad-iron, and also into the burner 31 and through the apertures 32 thereof into the 25 lower portion of the concavity 11. When a sufficient quantity of fluid has flowed from the tank, I close the closing-cap and discharge-port and ignite the fluid in the drip-cup and concavity, the burning of the fluid heating the generator, burner, supply-pipe, tank, and, 30 in fact, the entire device, except the wooden handle. When the free fluid is about exhausted, I open the discharge-port, and more fluid is expelled from the tank by the expansion thereof, which fluid flows through the 35 passage heretofore described to the vaporizing-ball and at that point is vaporized by the vaporizing-ball and the heated metal of the generator and discharged as inflammable vapor through the passage 29 and discharge-40 port into the burner 31 and through the apertures 32 of the burner downwardly into contact with the sad-iron immediately below the burner. I ignite the inflammable vapor at the point of discharge from the burner, and 45 thereby produce intense heat below the burner upon the sad-iron, which heat is disseminated through the different metal parts and communicated to a large degree to the tank or receptacle, maintaining such a degree 50 of temperature in said tank as to insure the expansion of the fluid therein to such an extent as to discharge all of said fluid through the apertures and into the concavity of the sad-iron in the form of inflammable vapor. 55 In the provision of a tank formed of a single piece of metal, preferably brass, by casting, I provide against the explosion or disintegration of the tank or separation of its members. 60 In the use of the vaporizing-ball in the well 65 I provide for the complete and perfect vaporization of the fluid in advance of its discharge from the discharge-port, because the vaporiz-

ing-ball is heated to a high degree and the fluid must pass around said ball in a thin sheet, to a maximum degree susceptible to the 70 heating influence of adjacent metallic bodies.

In the provision of the trap formed by the rear portion of the chamber 20 and in conjunction with the communicating passage 26, of very small diameter and located at a high 75 altitude relative to the bottom of the chamber 20, I have provision for depositing, precipitating, and retaining mineral substances, sediment, and foreign matter contained in the fluid, and thereby prevent clogging of the 80 minute passages 26 29 by such sediment or mineral substances. I also provide a screen 35 in the trap or chamber 20 to interrupt and prevent the flow of sediment to the well.

I claim as my invention— 85

1. A vapor-burning sad-iron, comprising an oil-tank, a sad-iron provided with a cavity, a generator mounted in the rear of said sad-iron and opening to the cavity therein, a supply-pipe connecting the tank and generator and carrying the tank, a burner fixed to the generator and extended into the cavity of the sad-iron and provided with downwardly-opening flame-ports, a trap-chamber in the generator at the discharge end of the supply-pipe and of greater diameter than said pipe, a minute communicating passage horizontally positioned in the upper portion of the generator and leading from the upper portion of the trap opposite the supply-pipe, a screen 100 in the trap, a well vertically formed in the rear portion of the generator, and receiving the discharge end of the communicating passage, a passage 29 and discharge-port at the lower end of the well, a needle-valve controlling the discharge-port, and a generating-ball in the lower end of the well, which ball is of slightly-less diameter than the well. 105

2. In a sad-iron, the generator having the cylindrical well, a horizontal discharge-passage below said well and an oblique passage leading from a point at one side of the central vertical plane of the well to and communicating with the horizontal discharge-passage near the terminal thereof, a needle - valve 110 mounted in and controlling the horizontal discharge-passage, a spherical ball of slightly 115 less diameter than the well mounted loosely in and resting on the bottom of said well, the point of contact of the ball and well-bottom 120 being at the central vertical plane of the well, means for supplying fluid to the generator and a burner attached to the generator. 125

3. In a device of the class described, a generator having a trap and a well, a minute passage between said trap and well, a vaporizing-ball located in said well, a discharge - port communicating with the well, and a needle-valve controlling said discharge-port.
